UNITED STATES PATENT OFFICE.

JAMES WHITCOMB, OF HASTINGS, NEBRASKA, ASSIGNOR OF ONE-THIRD TO EARL C. SIPPLE, ONE-THIRD TO BENJAMIN F. HEFFNER, ONE-TWELFTH TO RALPH S. BUCHTEL, ONE-EIGHTH TO JOE MANLEY DAVIS, AND ONE-EIGHTH TO CHARLES GARLAND LANE, ALL OF HASTINGS, NEBRASKA.

INTERNAL-COMBUSTION ENGINE.

1,333,693.

Specification of Letters Patent. Patented Mar. 16, 1920.

Application filed June 18, 1919. Serial No. 305,133.

To all whom it may concern:

Be it known that I, JAMES WHITCOMB, a citizen of the United States, resident of Hastings, Nebraska, have invented certain new and useful Improvements in Internal-Combustion Engines, of which the following is a specification.

My invention relates to improvements in internal combustion engines and aims to 10 provide a double acting four cycle engine of extremely simple, economical and desirable construction and high efficiency and the invention includes the novel features of construction and arrangement and combination 15 of parts hereinafter described and particularly defined by the appended claims.

An embodiment of my invention is illustrated in the accompanying drawings, in which—

20 Figure 1 is a plan view, partly in section, of my improved engine.

Fig. 2 is a central vertical section.

Fig. 3 is a transverse section on the line of the main shaft viewed from the left of Fig. 1.

Fig. 4 is a detail view of the cam action.

Fig. 5 is a detail view of the spark control.

Fig. 6 is an end view, and

30 Fig. 7 a sectional detail of the cylinder head.

Referring by reference characters to these drawings, in which similar characters denote the same parts throughout the several views the numeral 1 designates a suitable 35 base upon which the engine parts are mounted and which is provided with three parallel vertical webs or flanges 1^a, 1^b and 1^c, two of which, 1^a and 1^b, extend approximately the entire length of the base.

40 Upon the webs 1^a and 1^b at one end of the base is mounted the engine cylinder which is constructed of a plurality of parts detachably bolted together and of such construction as to enable them to be very easily and 45 economically manufactured.

This comprises a main cylinder 2 forming the combustion chambers, an outer cylinder 3 forming the water jacket, and the heads 4 and 5.

50 The main or inner cylinder 2 is provided with outwardly extended annular flanges 2^a to which the cylinder heads are bolted and these flanges also serve to support the water

jacket cylinder and hold the same spaced from the main cylinder to provide the intervening water space as shown. 55

The cylinder heads are provided with properly ground annular rabbets as indicated at 4^a and 5^a, to form seats for the ends of the cylinders, suitable packing being interposed as indicated at 6.

The cylinder heads are provided with transversely disposed enlarged portions which are provided with inlet and exhaust passages designated *a* and *b* respectively 65 which extend inward from opposite sides of the heads and curve inward to enter the cylinder lengthwise thereof, their inner ends being shaped to form, or provided with, suitable valve seats for the inlet and exhaust 70 valves 7 and 8. These valves are provided with valve stems 7^a and 8^a which extend through the cylinder heads and are provided upon the exterior portions with springs 7^b and 8^b which tend to keep the 75 valves seated. The inlet valves are intended to be opened by suction, the exhaust valves being controlled by cams operated in the manner hereinafter described.

To the inlet passages are connected in any 80 suitable or desired manner the ends of an inlet manifold 9 which has a portion, conveniently in the shape of a T coupling 10 designed to be connected to a carburetor of the ordinary or any approved design which 85 is indicated conventionally at 11.

A similarly constructed exhaust manifold 12 is connected to the exhaust passages on the opposite side of the engine.

The cylinder heads are provided with laterally extending lugs or flanges 4^x and 5^x which are designed to be bolted to the webs or flanges 1^a and 1^b heretofore described. 90

The reduced or thinner portions of the heads above the port enlargements are provided with threaded openings for the reception of the spark plugs indicated at 13. 95

The cylinder head 5 is provided with a central opening through which passes the piston rod 14, the cylinder head being provided with an annular flange extension forming an elongated bearing for the piston rod which is encircled within the bearing by a packing ring 15, preferably of the piston ring type. 100

To the piston rod within the cylinder is 105

connected the piston 16 which is provided with suitable packing rings as shown and which is designed to divide the cylinder space into two combustion chambers as 5 clearly shown in Figs. 1 and 2.

The opposite end faces of the piston are recessed as indicated at 16^a and 16^b.

The forward or outer end of the piston rod 14 is suitably connected to a cross head 10 17, the ends of which rest upon the upper faces of the webs or flanges 1^a and 1^b, which are suitably planed or ground to provide smooth bearing faces, and the upper sides of the cross head ends are engaged by the 15 longitudinal bars 18 bolted to the webs 1^a and 1^b with interposed spacing blocks 18^a, the space between these bars 18 and the cross head ends or arms forming cross head guides.

20 The webs or flanges 1^b and 1^c are provided with bearings 19 and 20 in which is journaled the main shaft 21 which carries at one end a crank disk 22 and at the other end a fly wheel 23 which may be constructed to 25 serve as a band pulley.

A pitman or connecting rod 24 has one end pivotally connected to the cross head as indicated at 24^a and its other end connected to the disk 22 by a wrist or bearing 24^b 30 connected to the disk eccentric of the axis thereof.

Journaled in suitable bearings in the webs or flanges 1^b and 1^c parallel with the main shaft is a counter or cam shaft 25 which is 35 driven from the main shaft by two to one gearing indicated at 26, and this shaft carries cams 27 and 28 for operating the exhaust valves and also the rotary element of the timer which is indicated conventionally 40 at 29.

The cams 27 and 28 are similarly constructed as shown in detail in Fig. 4. They are adapted to operate with a wiping action on push rods 29' and 30 guided in suitable 45 brackets 29^a and 30^a supported from the engine base. Each push rod is provided with a cam contact member 28^a rigid thereon which is provided with an inclined face adapted to be pushed into contact with the 50 cam, and a flat face adapted to subsequently bear on the cam, as shown in Fig. 4. The outer end of push rod 29' is adapted to actuate rocker arm 31 which in turn actuates the valve stem 8^a of exhaust valve 55 8, the rocker arm being pivotally mounted on a post carried by the cylinder head.

The push rod 30 has pinned thereon the two arms of a forked member 32, the single arm or stem of which is arranged to actuate the exhaust valve in the head 5. 60

The oscillatory element of the timer is connected by a link 33 with a hand lever 34 operating over a quadrant 35 as shown in Fig. 5.

Having thus described my invention, what 65 I claim is:

1. In an internal combustion engine, a base having vertical webs, and a cylinder having heads provided with laterally extending lugs or flanges resting upon said webs and bolted thereto. 70

2. In an internal combustion engine, a base having vertical parallel webs, a cylinder having heads supported from said webs, a piston, a piston rod projecting through 75 one of the heads, a cross head to which said rod is connected, said cross head having portions slidably supported on said webs, and guide bars carried by the webs and bearing on the upper surfaces of said cross head. 80

3. In an internal combustion engine, a base having a plurality of vertical parallel webs, a cylinder supported upon two of said webs, a cross head slidably supported on said two webs, a piston in the cylinder 85 having a rod connected with said cross head, a main shaft journaled in bearings supported by one of said webs and another web, a cam shaft journaled in bearings carried by said last named webs and driven from said 90 main shaft, a pitman connecting the cross head with a crank pin connected with said main shaft, valves in the cylinder heads, and push rods slidably supported from said bed and arranged to be operated by said 95 cams, and means whereby said push rods operate said valves.

4. A double acting internal combustion engine having inlet and exhaust valves in the opposite ends thereof, a main shaft, a cam shaft driven from said main shaft, and having a pair of oppositely disposed adjacent cams, a pair of slidable parallel push rods having contact members coacting with said cam, a rocker arm operatively engaging the exhaust valve stem of the outer cylinder end and one of the push rods, and a rigid member carried by the other push rod and operatively engaging the exhaust valve in the inner end of the cylinder. 100 105 110

In testimony whereof, I affix my signature.
JAMES WHITCOMB.
